UNITED STATES PATENT OFFICE.

AUGUSTUS F. KRUSER, OF NEW YORK, N. Y.

MAIL-BAG-TRANSFER DEVICE.

1,078,789.

Specification of Letters Patent. Patented Nov. 18, 1913.

Application filed March 27, 1913. Serial No. 757,152.

To all whom it may concern:

Be it known that I, AUGUSTUS F. KRUSER, a citizen of the United States, and a resident of New York, borough of Queens, in the 5 county of Queens and State of New York, have made certain new and useful Improvements in Mail-Bag-Transfer Devices, of which the following is a specification.

My invention relates to a new and useful 10 improvement in mail bag transfer devices and more especially to a device of this character that not only delivers a mail bag to a moving train but simultaneously receives one therefrom.

15 Hitherto as far as I know devices have been used whereby the mail bag is hung and grasped by an arm attached to the moving train, and the bag to be delivered at this point or station is thrown or kicked from 20 the car door. It will be readily seen that this is followed by ill consequences to any fragile mail that may be in the bag and also wearing and destructive on the bag itself and has often times resulted in the total 25 destruction of the mail and bag by rolling beneath the wheels of the moving train.

An object of this invention is to do away with the simple tossing of the bag from the moving train.

30 Another object is to provide mechanism that will deliver a bag of mail to the moving train and at the same time receive one therefrom.

Another object is to provide a device that 35 will receive and deliver the mail bags and swing from its receiving and delivering position, so that no one may be injured if his head or arms protrude from the windows or platform of the moving train.

40 Still another object is to provide a device of this character that will be cheap to manufacture, easy to construct and neat in appearance.

With these and other objects in view my 45 invention consists in certain new and novel constructions and combinations of parts as will be hereinafter more fully described and pointed out in the claims.

In the accompanying drawings forming a 50 part thereof similar reference characters designate corresponding parts throughout the several views.

Figure 1 is a view in perspective of my improved device and part thereof shown

fastened to the car, Fig. 2 is a side elevation 55 and partly in section of the car, Fig. 3 is a top plan view showing a fragmental portion of the car, Fig. 4 is a detail view of the striking post or striking mechanism, Fig. 5 is an enlarged view in elevation of the bag 60 receiving mechanism that is secured to a standard, Fig. 6 is a detail view in elevation of a delivery member that is also attached to the standard, Fig. 7 is also a detail view of the delivery member that is attached to the 65 car, Fig. 8 is a detail view in elevation of the receiving member that is attached to the car, Fig. 9 is a top plan view of both sets of receiving and delivering members in engagement, and Fig. 10 is a top plan view of the 70 lower receiving arms as shown in Fig. 5.

Referring now to the drawings, 1 is a base plate that may be secured to the ground in any preferable manner and 2 is a standard or post set therein and adapted to rotate 75 about a vertical axis. A rod 3 is horizontally and rigidly secured to the standard 2 and preferably near its top as shown at 4, and at a suitable distance below the rod 3 a hollow rod or what I term casing 5, is secured to the standard 2, the inner end thereof passing therethrough as shown at 6. Braces 7 and 8 are secured to the rod 3 and casing 5 to maintain the two in the same vertical plane, these braces may be secured in 85 any well known manner and as many used as found necessary. At a suitable distance below the casing 5 is secured a second casing 9 and likewise its inner end secured and passing through the standard 2 as at 10. 90

Adapted to movably fit within the casing 5 is a rod 11 and secured to the outer end thereof is a member 12 provided with a contact wheel or roller 13, the purpose of which wheel will appear hereafter. To the other 95 end of the rod 11 is pivoted a lever 14 which in turn is fulcrumed at the outer end of the post 15 which is secured to the standard 2. A spring 16 is shown secured at one end to the end of post 17, which is fastened to the 100 casing 5, and the other end of the spring 16 fastened to the outer end of the post 18, which is secured to one end of the rod 11. The purpose of this spring is to normally 105 force the rod 11 to its inner position and thereby force a rod 19, that is adapted to fit within the casing 9, and also pivoted to the lever 14 as at 20, in its outer position, it be-

ing apparent that any inward movement exerted on the rod 11 will be transferred into an outward movement of the rod 19 and also proportionately increased as the fulcrum of the lever 14 is at its upper end.

The lever 14 is slotted (Fig. 2) where the ends of the arms 11 and 19 are pivoted, so that there will be no binding action when the arms are actuated. Passing through the standard 2 and below the casing 9 is a rod 20 and pivoted to one end thereof is a bar 21 which is fulcrumed to a post 22 secured to the standard 2, and at the other end of the rod 20 is a cap or head 23, and secured to this head 23 a tension spring 24. A stop 25 is securely fastened to the base plate 1 and against which the lower end of the arm 21 is adapted to contact when set, and said arm is released when the standard is rotated by the striking action received from the car and also by the lower end 26 of the lever 14 striking the cap or head 23. Also secured to the base 1 is the semi-circular track or guide 27 and sliding or moving within this track 27 is a post 28, fastened at its lower end to the lever 29 which is pivoted to the base 1 at 30. It will be noticed that this lever 29 is pivoted half way between the ends of the hemispherical track. At the upper end of the post 28 is fastened one end of a spring 31 and its other end to a post 32 that is secured and projects from the standard 2. A stop 32 similar to 25 is also shown secured to the base plate 1, (Fig. 1).

From the foregoing it will be seen that when the lever 29 is set at the left hand side of the semi-circular track the spring 31 will turn the standard, when released, and the arms 3, 11, 19, etc., to the right; and when the lever 29 is set to the right hand side of the semi-circular track, the standard 2 and arms 3, 11, etc., will be swung to the left.

Referring now to the rod 19, it will be seen that formed integrally thereon are two extending arms 34 and 35 and pivoted to the end of arm 24 is a member 36 and to arm 35 a member 37. The preferable mode of securing the members 36 and 37 to the ends of these arms is by reducing the said ends of the arms 34 and 35 and providing these members 36 and 37 with bifurcated arms 38 and 39 clearly shown in Fig. 5, the reduced portion of the arms 34 and 35 fitting within the respective arms of the members and a pin or bolt 40 passed therethrough. Fastened to the end of the upper arm 38 of each member is a post 41 to which is secured a spring 42 which in turn is fastened to a post 43 secured to the arm 34. It will be understood that these two members 36 and 37 are both pivotally secured in the same way to the arms 34 and 35 and therefore describing the manner of pivoting by securing one applies also to the other. The object of

pivoting these members in this manner is that they may swing slightly, when thrust into engagement with their corresponding members which will be hereinafter explained.

Taking up now the construction of the member 36, which is a receiving member, it will be seen that it is formed with an upper portion (Fig. 5) 44, lower portion 45, and back 46, and to the back portion is secured the arm 34 as heretofore explained. In the face of these upper and lower portions 44 and 45 are cut two V shape grooves (Fig. 1) and pivoted on the top of the upper portion 44 are two small retaining arms or hooks 47 and 48 which are held normally closed by a spring 49, and similar retaining arms or hooks 50 and 51 are also secured to the under face of the lower portion 45 and also held closed by a similar spring 52.

Secured to the lower portion 39 of the member 36 is a depending post 53 and to which is secured, at its lower end, a cross bar 54, to the ends of which are pivoted two arms 55 and 56, said arms normally held open by a spring 57. Passing through the post 53 is a plunger 58 provided at one end with an enlarged head 59 and at the other end with a partly wedge shaped head 60. The object of these arms and plunger is to close these arms when a mail bag strikes the plunger head, and retain them in their closed position until the mail bag is taken therefrom.

Referring now to the delivery member 37 it will be seen that this is similar to the member 36 with the exception that instead of retaining or gripping hooks (Fig. 3) U shaped springs 61 and 62 with slightly diverting ends are secured to the upper and lower portions (Fig. 6).

Referring now to the delivery and receiving members 63 and 64 that are attached to the car, (Figs. 1, 3, 7, 8) it will be seen that they differ only from the members 36 and 37 in that, instead of pivoted to an arm they are each fastened to a rod (Fig. 7) 65 which extends through a casing 66, in which there is located a spring 67 that presses against a washer 68 secured to the rod 65 and also against the inside of the casing 66 thereby normally holding the member in its foremost position. Only one pair of retaining hooks 69 for the receiving member is found necessary. These members 63 and 64 are secured to a bar 70 that extends horizontally across the car opening and extend when in their foremost position, about four inches from the side of the car, as I have found that a car does not rock or sway more than four inches from its normal vertical position. By providing these members with plungers as illustrated the swaying of the car is allowed for and relieves the shock to all parts of the mechanism which will be present when the

130

car is traveling at a high rate of speed; and it will also be noticed that the pairs of delivery and receiving members are oppositely located with respect to each other. Also the 5 receiving members are both larger than the delivering members so that the delivering member may pass within the receiving members when they are thrust into engagement.

To support the mail bags in their respective members I provide small posts or pins, that are formed with an enlargement 72 thereon so that they will be sustained by the V shaped arms of the different members and secured to the bottom of the pin is provided 10 preferably a snap hook 73 which is adapted to engage with any ring, hook or handle on the end of a mail bag.

Describing now the striking post or what is really the timing mechanism it will be 15 seen that securely fastened to the roof of the car is a bed plate through which projects for a short distance, a post or member 75 which is adapted to rotate eccentrically, and this is accomplished by securing the same to a 20 rod 75 (Fig. 4) and at a point slightly off its center. To the lower end of this rod is secured a ratchet and crank 76 and 77, and to mesh therewith is a ratchet 78, and also secured to the rod 75 is a washer 79 and 25 spring 80. The necessity of having this post adapted to swing in the manner mentioned, is that the mechanism may operate correctly 30 regardless of the direction of the moving train, and as the bar 3 must be exactly at right angles to the train when the arm 19 is forced farther forward, it is necessary to 35 secure the post the distance of one half the thickness of the arm 3 to one side of the arm 3 when the same is at right angles to the 40 car. Also secured to the side of the car is a protruding obstruction or cam 81 decreasing 45 in width from the center toward each end and the widest or most extended portion being directly under the post 74, and this cam or protrusion 81 is formed with a 50 sufficient width to force the receiving and delivering members into engagement as will hereafter be explained.

Now setting out the operation; assuming 55 the train is running from the right to the left (Fig. 1), lever 29 is thrown to the left and secured by a notch or lock (not shown), the standard 2 is swung to the left, the lever 21 pulled away from the post and inserted in 60 front of the stop 25, a mail bag is secured to a small pin or post by the snap hook and placed within the member 37 as clearly shown in Fig. 1. Likewise secured in the delivering member in the car is another mail bag. When the post 74 strikes the arm 3 it 65 naturally swings the arm in the direction of the moving train, the roller 12 contacts with the projection 81 forcing the rod 11 inwardly and the arm 19 with the members 36 and 37 forward, and at the same time the

end 26 of the lever 14 strikes the head 23 on the rod 20 and the spring 24 retains the lever 21 in the position shown in Fig. 2, so that after the train has passed, the standard 2 and its attached arms swing back parallel to the track and out of the way of any other oncoming train. When the rod 19 advances as the striking post moves the arm 3 and when the arm 3 is exactly at right angles with the train the rod 19 will be at its most outward position and the respective delivering and receiving members thereby forced in their engaged position as shown in Fig. 2 and in Fig. 10, although in the latter view the pins with the mail bags attached are not shown in position. It will be seen that the 70 spring hooks 47, 48, and 50 and 51 of the member 36 engage, or grasp and retain the pin with the mail bags secured thereto, also the lower portion of the bag strikes the 75 plunger head 59 and holds the arms 55 and 56 securely around the bag, so that it will not strain the hooks 47, 48, 50, and 55 when the post and arms fly back parallel with the track as heretofore explained. At the same 80 time that the member 36 is grasping the mail bag from the moving train, the pin or post of the mail bag in the delivery member 37 is grasped by the arm 69 of the receiving member 64 in the car. If the train is to advance from the other direction the post 74 in the train is swung around and the lever 29 secured to the post also swung around and locked and the lever 21 set against the 85 stop 33. It will be understood that if the base and its attached mechanism is to be 90 stationed on a curve it will have to be set at a corresponding angle to the track so that the different delivering and receiving members may correctly engage with each other. 95

From the foregoing it will be seen that I have provided a device that is positive in its action, may receive and deliver mail to a rapidly moving train regardless of direction, and also a device that is so constructed 100 that it will not be destroyed by the jar produced from a post on a rapidly moving car striking part of the mechanism. Also by using plunger receiving and delivering members on the car the swaying of said car 105 is allowed for and as before explained the arms will swing to a parallel position with the track after the train has passed. If there is no mail to be delivered to the train and it is only desired to receive mail from 110 the same of course no bag will be placed in the delivering arm or (vice versa). Of course many changes of detail may be made without departing from the spirit and scope 115 of my invention.

Having thus described my invention what I claim as new and desire to secure by Letters Patent is:

1. In a mail bag transfer device the combination of, a standard, arms secured thereto, 120

means secured to one of said arms for delivering and receiving mail bags; means secured to a car for delivering and receiving the said mail bags and means secured to said car for contacting with the other one of said arms to thereby transfer the said mail bags.

2. In a mail bag transfer device the combination of, a standard, arms secured thereto, means secured to one of said arms for delivering and receiving mail bags; means secured to a car for delivering and receiving the said mail bags and means secured to said car for contacting with the other one of said arms to thereby simultaneously transfer the said mail bags.

3. In a mail bag transfer device the combination of, a rotatable standard, an arm secured to the standard, near the top thereof, casings extended horizontally therefrom, arms adapted to fit within said casings and connected by a lever, means secured to one of said arms for delivering and securing mail bags; means secured to a car for delivering and receiving the said mail bags, and means secured to said car for contacting with the other arms to thereby transfer the said mail bags.

4. In a mail bag transfer device the combination of a rotatable standard, means for setting it against rotation until released, an arm secured to said standard near the top thereof, casings extended horizontally therefrom, arms adapted to fit within said casings and connected by a lever, means secured to one of said arms for delivering and receiving the mail bags, and means secured to a car for contacting with the other arms to thereby transfer the said mail bags.

5. In a mail bag transfer device the combination of, a rotatable standard, an arm secured near the top thereof, casings extended horizontally therefrom, arms adapted to fit within said casings and connected by a fulcrumed lever, means for setting the said

45 standard against rotation, comprising, a stop secured to the base of said standard, an arm secured to said standard and a lever fulcrumed thereto, and pivoted to its upper end to a second arm provided with a tension spring; means secured to one of the arms adapted to fit within the casing for delivering and receiving mail bags; means secured to a car for delivering and receiving the said mail bags and means secured to said car for contacting with the other arms to thereby transfer the said mail bags.

6. In a mail bag transfer device the combination of, a rotatable standard means for setting it against rotation until released, and means for causing it to return to a left and right position, an arm secured to said standard, near the top thereof, casings extended horizontally therefrom, arms adapted to fit within said casings and connected by a lever, means secured to one of said arms

for delivering and receiving mail bags; means secured to a car for delivering and receiving the said mail bags and means secured to said car for contacting with the other arms to thereby transfer the said mail bag.

7. In a mail bag transfer device the combination of, a rotatable standard, means for setting it against rotation until released, and means for causing it to return to a left and right position comprising a semi-circular track secured to said base, a lever pivoted at its inner end to said base, guided at its outer end by said track and connected to said standard by a spring, said lever adapted to be locked at both ends of said track; an arm secured to said standard near the top thereof, casings extended horizontally therefrom, arms adapted to fit within said casings and connected by a lever, means secured to one of said arms for delivering and receiving mail bags; means secured to a car for delivering and receiving the said mail bags and means secured to said car for contacting with other arms to thereby transfer the said mail bags.

8. In a mail bag transfer device the combination of a rotatable standard, a horizontal arm secured to the standard near the top thereof, casings secured to said standard, arms adapted to fit within said casings, the inner ends of said arms being connected to a fulcrumed lever the outer end of said upper arm being provided with a contacting roller, the outer end of said lower arm formed into two projecting arms, a receiving member pivoted to one arm and a delivery member to the other; means secured to a car for receiving and delivering mail bags and means secured to said car for contacting with the arm secured near the top of the standard, and means adapted to contact with the said contacting roller to thereby transfer the mail bags.

9. In a mail bag transfer device the combination of, a rotatable standard, a horizontal arm secured to the standard near the top thereof, casings secured to said standard, arms adapted to fit within said casings, the inner ends of said arms being connected to a fulcrumed lever, the outer end of said upper arm being provided with a contacting roller, the outer end of said lower arm formed into two projecting arms, a receiving member pivoted to one arm and a delivering member to the other, and a spring secured to each of said members and said arms to retain said members in their normal position; means secured to a car for receiving and delivering mail bags, and a post secured to said car adapted to contact with the arm secured near the top of said standard to revolve the said standard, and a projection secured to said car to contact with said contacting roller to thereby force

the respective delivery and receiving members into engagement to thereby transfer the mail bags.

10. In a mail bag transfer device the combination of, a rotatable standard, a horizontal arm secured to said standard near the top thereof, casings secured to said standard, and arms adapted to fit within said casings, one of said arms having formed on its inner end two projecting arms, a receiving member pivoted to one of said arms, said member comprising an upper, back and lower portion, depressions in the outer faces, of the upper and lower portions, hooks pivoted to the upper and lower portions and means to normally hold the said hooks in their closed position; a delivering member secured to the other projecting arm, comprising an upper, back and lower portion, depressions formed in the outer faces of said upper and lower portions, and spring arms secured to said upper and lower portions; means secured to a car to contact with the arm secured near the top of said standard and means secured to said car to contact with an arm within one of said casings to thereby transfer the mail bags.

11. In a mail bag transfer device the combination of, a rotatable standard, an arm secured to said standard near the top thereof, casings secured to said standard and arms adapted to fit therein, receiving and delivering members secured to one of said arms; a receiving member secured to a car comprising an extensible bracket, depressions formed in the outer face of said bracket retaining hooks secured to the top of said bracket, and means for holding the hooks normally in their closed position means for normally holding the bracket in extended position; a delivering member secured to said car comprising an extensible bracket, depressions formed in the outer faces thereof and spring arms secured to said bracket, means for normally holding the bracket in its extended position and means for contacting with the horizontal arm, and means for contacting with one of the other of said arms to thereby transfer the mail bags.

12. In a mail bag transfer device the combination of, a rotatable standard, a plurality of arms supported thereby, a receiving and delivering member secured to one of said arms a rod depending from the receiving member, grasping arms secured to the lower end of said rod and means for holding these grasping arms in their open position; a receiving and delivering member secured to a car, and means secured to said car for contacting with two of said arms of the rotatable standard to thereby transfer the mail bag.

13. In a mail bag transfer device the combination of, a rotatable standard, a plurality

of arms supported by said standard, a receiving and delivering member pivotally secured to one of said arms, a rod secured to and depending from said receiving member, a cross bar secured to said arm, grasping arms pivoted to the ends of said cross bar, means for normally holding the gripping arms in their open position and a plunger passing through said cross arm provided with an enlarged wedge shaped head adapted to retain the grasping arms in their closed position when said plunger is forced inwardly; a receiving and delivering member connected to a car adapted to be forced inwardly when in the engagement with the first mentioned receiving and delivering members and means secured to the car for forcing the first mentioned receiving and delivering brackets inwardly to thereby transfer the mail bags.

14. In a mail bag transfer device the combination of, a rotatable standard a plurality of horizontal arms secured thereto, a lever pivoted to the outer end of two of said arms, a receiving and delivering member pivotally connected to the lower of said arms, a rod extending horizontally across an opening in a car, a receiving and delivering member yieldingly secured to said rod, a striking post secured to the roof of said car, said post adapted to rotate eccentrically and means for securing the post in a set position, a projection secured to the side of the car said projection decreasing in width from its center toward both ends and adapted to contact with one of the arms secured to the rotatable standard, to thereby force the respective receiving and delivering members into engagement and thereby transfer the mail bags.

15. In a mail bag transfer device the combination of a rotatable standard, an arm secured near the upper end thereof, casings secured to said standard and arms adapted to be supported by said casings, said arms connected at their one end by a fulcrum lever, said fulcrum being located near the upper casing, a bracket provided with a roller secured to the other end of the upper arm that is supported by one of the said casings, the lower arm formed with two projecting arms, a receiving bracket pivotally connected to one of said arms and a receiving bracket pivotally connected to the other, a bar extending horizontally across an opening in a car, a receiving and delivering member secured to said bar and oppositely arranged in respect to the first mentioned receiving and delivering members, a striking post secured to roof of said car and eccentrically secured to a depending shaft, a ratchet secured to the lower end of said shaft and a lever connected thereto, a second ratchet secured to said car and adapted to mesh with the ratchet connected to said

115
120
125
130

shaft, an enlargement in said shaft and a spring bearing against said enlargement and said car, to thereby retain the striking post in its set position; a projection secured to said car decreasing in width from its center toward each end and its center located in the vertical transverse plane with that of said striking post, said striking post and projection adapted to respectively engage the arms secured to the standard near the top thereof, and with the roller secured to the arm supported by the upper casing to thereby transfer the mail bag.

16. In a mail bag transfer device the combination of, a rotatable standard, a plurality of arms supported thereby, a receiving and delivering member secured to one of said arms, a pin provided with an enlarged portion and means for securing a mail bag attached to the lower end thereof, said pin adapted to be supported by the delivery bracket, a receiving and delivering member secured to a car, and oppositely arranged

with respect to first mentioned receiving and delivering members, a second pin provided with an enlarged portion and means for securing a mail bag secured to its lower end, and adapted to be supported by the delivery member, means secured to the car for contacting with the arms secured to the rotatable standard to thereby force the respective delivering and receiving members into engagement and transfer the pin, supporting the mail bag in the delivering member of the rotatable post, to the receiving members attached to the car, and the pin supporting the mail bag, in the delivery member attached to the car, to the receiving member attached to the rotatable standard.

Signed at New York, borough of Queens 40
in the county of Queens and State of New
York, this 24th day of March A. D. 1913.
